UNITED STATES PATENT OFFICE.

WARD RAYMOND, OF EASTON, PENNSYLVANIA, ASSIGNOR TO PENNSYLVANIA PUMP AND COMPRESSOR CO., OF EASTON, PENNSYLVANIA, A CORPORATION OF PENNSYLVANIA.

UNLOADER VALVE.

Application filed September 26, 1923. Serial No. 664,943.

To all whom it may concern:

Be it known that I, WARD RAYMOND, a citizen of the United States, residing at Easton, in the county of Northampton and State of Pennsylvania, have invented certain new and useful Improvements in Unloader Valves, of which the following is a specification.

This invention relates to unloaders for compressors and in particular to an unloader adapted to operate by retaining one of the compressor valves in an open position during the unloaded period.

An object of the present invention is to provide improved means within the body member of the valve mechanism to hold the valve in its open position.

Also, it is an object to provide a piston operating within a cylinder formed within a part of the valve mechanism, movement of the piston serving to force the valve to its open position through the medium of independent pins mounted within the valve body.

Another object of the invention is to provide means to facilitate assembling the valve bodies in their positions relative to each other and to hold them in this assembled position while they are being placed in position within a compressor cylinder.

With these and other objects in view, my invention consists in the features of construction and operation set forth in the following specification and illustrated in the accompanying drawings.

In the accompanying drawings annexed hereto and forming a part of this specification, I have shown my invention embodied in and forming a part of a compressor valve mechanism but it will be understood that the drawing is not to be construed as defining or limiting the scope of the invention, the claims appended to this specification being relied upon for that purpose.

In the accompanying drawing:

Figure 1 is a cross sectional view through the entire valve mechanism forming the present invention.

Fig. 2 is a plan view of the valve body, one half being shown with the cover plate broken away, and

Fig. 3 is a sectional view taken on line 3-3 of Fig. 1.

In the above mentioned drawing, I have shown but one embodiment of the inven-

tion but it will be understood however that modifications may be made therein without departing from the spirit of the invention.

Briefly, my invention in its broadest aspect comprises the following principal parts: first, a valve body member such as that forming an inlet valve of a compressor; second, a cylinder preferably formed in a yoke member; third, a piston adapted to operate in the cylinder; fourth, means moved by said piston and engaging the valve to force it to its open position; fifth, fluid pressure means admitted to the cylinder to actuate the piston; and sixth, means to temporarily retain the members forming the mechanism in assembled position while they are being placed in position within the cylinder.

Referring more in detail to the figures of the drawing at 10 is shown the wall of a compressor cylinder having a cylinder head 11. Within spaces formed between the walls of the compressor is an intake passage 12 in which is located the intake valve body 13. It will be understood that several of these intake valves may be provided but as the invention is completely shown in one, the other intake valves and other parts of the compressor are not shown.

The valve body 13 may be of any type adapted for a valve plate such as shown at 14. Adjacent the valve body 13 is the cover plate 15, space being provided for movement of the valve plate 14 and for the fluid being compressed. To retain the body member 13 and cover plate 15 together, a bolt 16 is provided having a nut 17 threaded thereto.

The valve body 13 is forced against its seat formed within the cylinder walls by means of a yoke member 18, the periphery of which at one end engages the periphery of the valve body 13. Against the opposite end of the yoke member 18, a screw 20 is adapted to bear. This screw 20 extends through a valve opening cover 21 adapted to be fastened in any desired manner to the cylinder walls 10. All of the above described means are or may be those usually found in compressors of usual construction.

Formed within the valve body 13 are a plurality of parallel holes through which extend pins 22. Each of the pins 22 is formed with a head 23 on one end which may enter recessed portions of the holes. In order to normally force the pins 22 in

one direction, springs are provided disposed between the recessed holes and the heads 23 of the pins 22.

As the particular valve shown in the drawing is made up of two concentric rings, the pins are arranged in two circles, one within the other so that the pins 22 will be disposed to contact with both of the valve rings 14. Preferably three equally spaced pins 22 are provided in position to contact with each of the valve rings 14.

Centrally within the yoke member 18 is provided a cylinder 25 within which may operate a piston 26. At the inner end of the piston 26 is a grid member 27 preferably formed integrally with the piston 26. This grid 27 has two concentric portions 28 adapted to contact with the heads 23 of pins 22. Radially extending arms 29 provide supports for the rings 28. From the above construction, it will be seen that movement of the piston 26 within its cylinder 25 will cause the rings 28 to bear against the pins 22 so that pins 22 will force the valve rings 14 to their open position. A cup washer 30 fastened to the piston 26 provides a pressure tight joint between the piston 26 and its cylinder 25. A spring 31 disposed between the nut 17 and an internal surface of the piston 26 normally forces the piston to a position retracted within its cylinder so that the valves 14 are free to operate.

To admit fluid pressure within the cylinder to force the piston 26 forward so that the valves 14 will be held from their seats, the following means are provided: Extending through the end of the yoke member is a hole 32 adjacent the retaining screw 20. Extending through the screw 20 in an axial direction is a hole 33 which is in alignment with the hole 32. Between the end surface of the yoke member 18 and the inner end of the screw 20 is an annular gasket 34. By admitting fluid pressure through the hole 33 from a pressure regulating device of any type, such as an auxiliary valve, the piston 26 may be forced to a position to hold the valves 14 open. So long as the valves 14 are open, no compression can take place at that end of the cylinder.

While the piston 26 is held in its normal retracted position during which compression takes place within the cylinder, it is advisable to prevent the fluid being compressed from entering the cylinder 25. For this purpose, ground surfaces 35 are provided at the open end of the cylinder and on the piston 26 thus providing a fluid tight joint between these parts.

At it would be extremely awkward to assemble all parts of the valve mechanism within its space in the walls of the compressor, I provide special means to retain the yoke member in place during the assembling process. Screws 40 of which two

or more may be provided are mounted radially within the yoke member 18. These screws may readily be adjusted manually so that their outer ends will contact with internal surfaces within the walls of the compressor. To aid in this particular, the outer ends of the screws are conically shaped so that they will easily engage the surfaces of the cylinder and upon being slightly tightened will retain the yoke member 18 and its attached parts in position. With these parts so retained in position, the cover plate 21 may be fastened in place and the screw 20 tightened.

Additional retaining members may be provided such as the screws 42 threaded into the periphery of the valve body 13. These screws 43, any number of which may be provided extending radially from the valve body 13, enter enlarged holes provided within the yoke member 18. With these screws 42 placed in position after the valve body 13 and yoke member have been assembled with the piston 26 and other parts in place, they are prevented from becoming disarranged and may readily be placed in proper position within the cylinder.

What I claim is:

1. An unloading device for compressors comprising in combination, a valve body adapted to be inserted in the compressor, a valve therein actuated during operation of the compressor, a yoke for supporting said valve body in position, a cylinder formed within said yoke, a piston movable therein, means to receive fluid pressure to move said piston, and means engaging the compressor walls to prevent separation of said valve body and yoke while the above mentioned parts are being placed in position.

2. An unloading device for compressors comprising in combination, a valve body adapted to be inserted in the compressor, a valve therein actuated during operation of the compressor, a yoke for supporting said valve body in position, a cylinder formed within said yoke, a piston movable therein, means to receive fluid pressure to move said piston, and a plurality of radially extending screws threaded in the valve body and loosely engaging the yoke whereby said valve body and yoke are prevented from separating while the above mentioned parts are being placed in position.

3. An unloading device for compressors comprising in combination, a valve body adapted to be inserted in the compressor, a valve therein actuated during operation of the compressor, a yoke for supporting said valve body in position, a cylinder formed within said yoke, a piston movable therein, means to receive fluid pressure to move said piston, and means on said yoke adapted to engage portions of said compressor adjacent the valve opening to prevent separation of

said valve body and yoke while the above mentioned parts are being placed in position.

4. An unloading device for compressors comprising in combination, a valve body adapted to be inserted in the compressor, a valve therein actuated during operation of the compressor, a yoke for supporting said valve body in position, a cylinder formed within said yoke, a piston movable therein, means to receive fluid pressure to move said

piston, and a plurality of radially extending screws mounted in said yoke and adapted to engage portions of said compressor to prevent separation of said valve body and yoke while the above mentioned parts are being placed in position.

In testimony whereof, I hereto affix my signature.

WARD RAYMOND.
